VALVED HEAD FOR SOOT BLOWERS

Fred C. Arey, Oak Park, Ill., and De Los E. Hibner, Jr., Dubois, Pa., assignors to Vulcan Soot-Blower Corporation, a corporation of Pennsylvania

Application May 20, 1933, Serial No. 671,951

9 Claims. (Cl. 122—392)

It is common practice, in the art of blowing soot from boiler tubes, to provide the tubular blowing or cleaning element with a head containing a valve to control the admission of the cleaning fluid thereto. Such valves are usually operated automatically upon the turning of the blowing or cleaning element to cause the jets of steam or the like to play over a considerable space. Where the opening of a valve is dependent upon a movement of the cleaning element, already initiated, it is difficult to effect a proper opening before the cleaning element has turned through a considerable angle and, consequently, in most prior constructions it has been necessary to turn each cleaning element through a considerable angular distance to secure a complete opening of its controlling valve. Not only is time lost by a delayed opening of the controlling valve but, unless great care is taken, there will be a zone of ineffective soot cleaning or blowing within the space served by each cleaning element.

The object of the present invention is to produce a simple and novel construction that will cause a quick opening of the valve in the head of a soot blowing or cleaning element, whereby the steam or other cleaning fluid will be admitted in maximum volume before the element has made more than a slight movement.

In many instances the operation of soot cleaning elements is manual, the element being turned by chains passing over sheaves or pulleys. One of the objects of the present invention is to produce a simple and novel valve-operating mechanism which will cause the valve to open quickly after a pull comes on the chain or the like and to be thereafter unaffected by subsequent movements of the chain or other operating member to bring about the desired adjustments in the position of the cleaning element, until the cleaning element reaches a position in which the valve should again be closed.

The various features of novelty whereby our invention is characterized will hereinafter be pointed out with particularity in the claims; but, for a full understanding of the invention and of its objects and advantages, reference may be had to the following detailed description taken in connection with the accompanying drawings, wherein:

Figure 1 is an end view of a head for a soot cleaning element and its operating means, embodying the present invention; Fig. 2 is a vertical transverse section through the head on a plane at right angles to the long axis of the cleaning element or, approximately, on line 2—2 of

Fig. 3; Fig. 3 is a longitudinal vertical section taken approximately on line 3—3 of Fig. 1; Fig. 4 is a section on line 4—4 of Fig. 3; Fig. 5 is an elevation, illustrating the opposite side from that appearing in Fig. 3, only a portion of the apparatus being shown, and a fragment of the head appearing in section; Fig. 6 is a section on line 6—6 of Fig. 3, some parts that would otherwise appear in section being shown in elevation; Fig. 7 is a section, on an enlarged scale, on line 7—7 of Fig. 4; Fig. 8 is a view similar to Fig. 4, but on the larger scale of Fig. 7, showing the moving parts in different positions than in Fig. 4, and the head proper being omitted; Fig. 9 is a view similar to Fig. 8, and showing the parts in still other positions; Fig. 10 is an elevation of a fragment of the head, showing a pilot valve; Fig. 11 is a central longitudinal section through that part of the apparatus shown at the right-hand end of Fig. 3 and embodying the step by step turning means for the cleaning element; and Fig. 12 is a section on line 12—12 of Fig. 11.

Referring to the drawings, 1 represents a hollow head to the lower end of which may be attached a steam pipe or conduit, not shown. Rotatably mounted in the upper end of the head is a tubular member 2 which will be referred to as the cleaning element, although usually it will be a part arranged end to end with and fixed to the cleaning element proper. The inner open end of the cleaning element communicates with the chamber A in the interior of the head through a stationary sleeve or bushing 4 fixed in the wall of the head adjacent to said end of the cleaning element. Normally, when the cleaner is idle, communication between the cleaning element and the interior of the head is shut off by a disk-like valve 5 fitting against the flat end face of the bushing or sleeve 4. This valve is connected to and carried by a piston 6 coaxial with the cleaning element and movable from and toward the latter in a cylinder 7. Any suitable connection may be employed between the piston and the valve, as long as it will permit the valve to adjust itself to its seat under the pressure of steam or other fluid within the head, and will cause the valve to move away from its seat as the piston recedes into its cylinder. In the arrangement shown, the valve has a short central stem 8, provided at its free end with a head 9. The stem 8 is movable into and out of a vertical slot 10 opening out through the top of a boss 11 on the forward end of the piston. Behind or inwardly from the slot 10 is a wider pocket 12 which also opens out through the top of the boss; this

5 pocket being of the proper dimensions to receive the head on the valve stem when the stem is slipped down into the slot. Behind the piston is a spring 13 which tends constantly to force the 10 piston into a valve-closing position and thus cause the valve to be seated and shut off communication between the interior of the head and the 15 cleaning element.

10 When the fluid pressure on opposite sides of the piston is equal, the spring is effective to hold the valve closed. However, when the interior of the cylinder 7 is connected to atmosphere and steam or other fluid under pressure is admitted into the head, the pressure on the valve 15 end of the piston will overcome the spring and cause the piston to be forced back into its cylinder and the valve to be unseated. In accordance with the present invention, the interior of the cylinder, behind the piston, remains in communication with the interior of the head at 20 times when the valve is to remain closed and is opened to atmosphere at and during the times the valve is to remain open. As best shown in Fig. 3 the cylinder is provided with a lining 25 sleeve 14 having two ports 15 and 16 extending through the same and opening into a chamber 17 in the wall of the head. The port 16 is a small one close to the rear end of the cylinder, whereas the port 15 is larger and is located not 30 far from the inner end of the piston when the latter is in its valve-closing position. Assuming that the cylinder is filled with steam and that the chamber 17 is connected to atmosphere and, also, that the interior of the head is filled with 35 steam under pressure: It will be seen that the pressure of the steam in the head will force the piston back, causing the steam in the cylinder to escape through the ports 15 and 16. Before the piston has gone very far, the port 15 will be closed, so that further escape of steam from the cylinder can only take place through the port 16 which is comparatively small. The 40 result is that the piston moves back rapidly in order to produce a complete opening of the valve, and then slows down to avoid striking a hammer blow against the rear piston head.

45 The parts heretofore described, with the exception of the dash pot control of the piston, are substantially the same as those disclosed in the 50 application of Fred C. Arey, Serial No. 604,382, filed April 11, 1932; and the admission of steam to and its exhaust from the chamber 17 and the cylinder is controlled by a pilot valve as in the aforesaid application.

55 The pilot valve embodies a little piston 20 slidable within a cylinder 21 that may conveniently be in the form of a thimble fixed in a wall of the head. The piston has a stem 22 that extends out through one end of the cylinder. One 60 end of the pilot valve cylinder is connected to the interior A of the head through a port 23, as best shown in Figs. 2 and 7; whereas the other end of this cylinder is connected to atmosphere through a port 24 leading from a 65 small cylindrical chamber 25 opening out of that end of the cylinder. At the juncture of the cylinder 21 and chamber 25 is a valve seat 26 adapted to cooperate with a valve face 27 on the piston 20. Whenever there is steam in 70 the head, it enters behind the piston 20 of the pilot valve device and, if the piston is free to permit it to do so, moves the piston into the position shown in Figs. 4 and 7, so that the valve elements 26 and 27 cooperate with each 75 other to shut off the cylinder 21 from the at-

mosphere. In order that the chamber 17 and the main valve cylinder 7 may be connected either to the interior of the head or to atmosphere, through the pilot valve device, the chamber 17 is connected with a chamber 28 beside the pilot valve cylinder 21, by a pipe 29. The chamber 28 is in turn connected to the interior of the cylinder 21 by a port 30 so placed that, when the piston 20 is at one end of its stroke, the port 30 lies on one side thereof whereas, when this piston is at the other end of its stroke, the port 30 lies on the opposite side thereof. In other words, when the pilot valve piston is at the left hand of its stroke, as viewed in Figs. 4, 7, 8 and 9, closing off communication with atmosphere, the main cylinder 7 is in communication with the interior of the head and the main valve is held closed. This is the condition illustrated in Figs. 4 and 7. When the stem of the pilot valve device is 20 pushed in, bringing the piston 20 into the right-hand end of the cylinder 21, as shown in Figs. 8 and 9, the main cylinder 7 is connected to atmosphere so that the steam exhausts from the main cylinder and permits the piston there- 25 in to be pushed back against the resistance of the spring 13.

It will thus be seen that the pressure in the system tends constantly to move the pilot valve into a position that will cause the main valve 30 to be closed, so that provision need only be made to push the stem of the pilot valve device in in order to bring about both closing and opening movements of the main valve.

In the arrangement shown, the cleaning element 35 is adapted to be turned by pulling on a chain 32 passing over a sheave or pulley 33 fixed to a shaft 34 extending parallel with the cleaning element just above the pilot valve device. This shaft is utilized to operate the pilot valve during 40 the first part of an operating movement of the sheave or pulley. This is accomplished by a small eccentric 35 fixed upon the shaft 34, the eccentric acting on a suitable element for pushing in the stem of the pilot valve. This element 45 may conveniently consist of a sleeve 36 surrounding and rotatable on a short stub shaft 37 projecting from the side of the head near and parallel with the shaft 34; the sleeve having thereon a dog or arm 38 in position to engage with the outer end of the valve stem 22 and having also a second radial arm 39 in the plane of the eccentric. The parts are so proportioned that, when the shaft 34 is turned, the eccentric will engage 50 with the arm 39 and cause the sleeve 36 to rock in the proper direction and through the necessary angular distance to push the stem of the pilot valve inwardly from its normal position illustrated in Figs. 4 and 7 to the position illustrated in Figs. 8 and 9. When this has been done the 55 main valve automatically opens, as heretofore explained. Furthermore, if the rocking valve actuator be locked in the position into which it has been moved by the eccentric, the shaft 34 may be turned in either direction and through any desired number of revolutions, at will, without further affecting the pilot valve. We have provided means for locking the pilot valve actuator in its working position, which means are under the control of the cleaning element so as 60 to trip or release the pilot valve actuator after the cleaning element has completed a predetermined movement or set of movements.

Mounted on the head above and parallel to the shaft 34 is a long stationary shaft 41 which may 65

be one of the bolts connecting the head and a casing 40 that contains the ratchet drive for turning the cleaning element, as will hereinafter be described. Surrounding the shaft 41, as best shown in Fig. 6, is a spacing sleeve 42 extending between a surface on the head and an opposite surface on the casing for the ratchet mechanism. Surrounding and rotatable on the sleeve 42 are two additional sleeves, 43 and 44, placed end to end and being independently rotatable on the sleeve 42. The sleeve 43 is short and lies just over the eccentric 35. The sleeve 44 is comparatively long and has thereon, surrounding its end remote from the sleeve 43, a torsion spring 45, one end of which is fixed thereto, as indicated at 46, whereas the other end is fixed to the casing or housing 40, as indicated at 47. At the meeting ends of the sleeve 43 and 44 are annular flanges or collars 48 and 49, respectively. The collar 48 has projecting therefrom a radial arm 50 provided at its free end with a laterally-projecting lip 51 which overlies the arm 39 of the pilot valve actuator. The arm 39 has at the top an upwardly-projecting lug 52 located at the outer or rear end. When the pilot valve actuator is swung into the position to hold the valve stem in, the lip 51 may drop in front of the lug 52, as shown in Figs. 8 and 9; thus locking the actuator against a return movement until the lip is again lifted clear of the lug. The locking of the pilot valve in the position illustrated in Fig. 8 is accomplished automatically upon the shifting of the valve into that position. The release of the pilot valve, so as to permit steam pressure to return it to the position illustrated in Fig. 4, is controlled by the cleaning element.

On the sleeve 44, remote from the flanged end, is an arm 53 projecting radially past the tubular cleaning element. The arm 53 is shown as having at its free end a laterally-projecting flange or lip 54. Fixed on the tubular cleaning element is a collar 55 located so as to contact with the lip or flange 54. On the collar is a cam projection 56. It will thus be seen that, through the action of the cam lug 56 on the flange or lip 54, a turning movement of the sleeve 44 may be effected. This turning movement is utilized to trip the catch or latch that locks the pilot valve. To this end there is pivoted to the collar 49 on the sleeve a dog 57 in the form of a flat plate, having its periphery properly shaped. This dog has a nose 58 which, in one angular position of the sleeve 43 relatively to the sleeve 44, drops behind a radial shoulder 59 in the under edge of the collar 48. At other times this nose simply rides upon the periphery or edge of the collar 48. A tension spring 60 extends between the free end of the dog 57 and the arm 50 on the collar 48, so as always to hold the nose of the dog pressed against the collar and ready to drop into the notch that produces the shoulder 59, when otherwise free to do so.

At the end of a soot blowing or cleaning operation the parts are in the positions illustrated in Fig. 4; the stem of the pilot valve projecting from the valve casing as far as it will go; the valve actuator being free from the latch, and the flange or lip 54 resting against the cam lug 56 on the cleaning element. Upon pulling the chain, the first thing that occurs is that the stem of the pilot valve is pushed in, as shown in Fig. 8, permitting the steam behind the piston for the main valve to exhaust and the main valve to open. As the pilot valve is being shifted, the nose 52 on the actuator travels along underneath the lip

or flange 51 on the latch device, until it passes beyond the end of the same. Thereupon the spring 60 acts to draw the latch device quickly down into the latching position illustrated in Fig. 8. A continued pull on the chain, as will hereinafter be explained, causes the cleaning element to turn in the clockwise direction, as viewed in Fig. 8. When this occurs, the torsion spring 45 on the sleeve 44 turns this sleeve in a counter-clockwise direction, keeping the flange or lip 54 in contact with the collar 55, as illustrated in Fig. 10. This angular movement of the sleeve 44 is sufficient to carry the dog 57 around to the point where the nose thereof drops behind the shoulder 59 on the latch device, as illustrated in Fig. 9. The parts remain in the positions just described until the cleaning element has completed a predetermined angular movement in one direction and has again returned to the starting position. As the cleaning element approaches its initial or starting position, the cam lug again engages the lip or flange 54, pressing it outwardly and causing the sleeve 44 to be turned in the clockwise direction. During this turning movement of the sleeve 44, the dog 57 acts as a driving element, through its engagement with the shoulder 59, to swing the latch in the clockwise direction and lift it clear of the lug 52 on the valve actuator. There being now no longer anything to hold the valve actuator, the pressure of the steam behind the piston of the pilot valve forces the piston toward the left, shutting off communication between the main valve cylinder and atmosphere and admitting steam under pressure to that cylinder so as to cause the main valve to close. The dog 57 must be moved out from behind the shoulder 59 in order to return the parts to the positions illustrated in Fig. 4 and thus make them ready for a repetition of the cycle of operations just described. To this end there is mounted on the arm 39 of the valve actuator a pin 61 that projects from the side thereof across the upper edge of the dog 57. The parts are so proportioned that, after the latch has been raised so as to release the valve actuator, the swinging of the valve actuator in the clockwise direction, as viewed in Fig. 4, through the action of the pilot valve, causes the pin 61 to strike the upper edge of the dog near the free end of the latter and force the dog out of the notch in the collar 48 and clear of the shoulder 59 forming one side of the notch. Thereupon the spring 60 acts to draw the latch arm 50 down until the lip or flange thereon rests on the lug 52 and the nose of the dog rests on the periphery of an unmutilated part of the collar 48.

The tubular cleaning element may be driven in any suitable way from the shaft 34. We prefer that the movements of the cleaning element be step by step and that, after the element has been turned through a predetermined angle, it can be brought back again step by step. The driving mechanism between the shaft 34 and the cleaning element that we have illustrated is that disclosed in the Fred C. Arey application, Serial No. 640,373, filed October 31, 1932, and is shown in sufficient detail in Figs. 11 and 12, herein, for the purposes of the present invention.

Referring to Figs. 11 and 12, it will be seen that there is fixed to the cleaning element, within the casing or housing 40, a toothed wheel 70. Loosely supported on the cleaning element beside the wheel is a rocking member 71. Pivoted to the member 71, as indicated at 72, is a double-ended balanced pawl having two pawl arms 73 and 74,

respectively. The pawl is provided with a wide, comparatively deep groove or channel 75 extending across the same midway between the pawl arms. In this groove or channel lies a roller 76, 5 on the end of a crank pin 77 carried by a crank arm 78 on the end of the shaft 34. As will be seen from Fig. 11, the axes of the pivot pin 72 and the shaft 34 are displaced a short distance from each other, this distance being somewhat 10 less than the radius of the crank. With this arrangement, as explained in the aforesaid application, 640,373, as long as the shaft 34 is turned in one direction, one of the pawl arms is effective to drive the toothed wheel step by step in the 15 same direction; and, when the direction of rotation of the shaft 34 is reversed, the other pawl becomes effective to drive the toothed wheel step by step in the reverse direction. The toothed wheel has thereon a block 79 which may be adjusted into any one of numerous positions angularly of the wheel; this block being adapted to 20 strike against a stationary stop 80 to limit the turning movements of the wheel. By providing two of these blocks, not only will the cleaning element be permitted to oscillate back and forth through any desired predetermined angle, but the starting and finishing points for a complete cycle 25 will always be such that the cam lug 56 will be in the position illustrated in Figs. 4 and 8. The 30 pawl-carrying member 71 is provided with a suitable brake that will afford sufficient resistance to turning movements of this member to permit the pawl device to be swung into tooth-engaging position before the rocking pawl carrier begins 35 to move. In the arrangement shown, the brake consists of a pair of brake shoes 81 and 82 engaged with the hub portion of the member 71 and carried on lever arms 83 and 84, respectively; each of these arms being fulcrumed at one end 40 on a stationary lug or post, as indicated at 85 and 86; and there being a tension spring 87 between the other ends of the arms.

It will thus be seen that we have produced a 45 simple and novel means for causing a valve to open quickly, simultaneously with the beginning of a turning movement of a soot cleaning element and to remain open until the completion of predetermined angular movements of the cleaning element, whereupon the valve automatically 50 closes and the mechanism is restored to a condition to permit the cycle of operations to be repeated whenever desired. It will also be seen that our improved valve-operating means is not limited to a construction and arrangement in 55 which a manually operated member performs no other function than to initiate a cycle of operations; since the manual controller, in the form of a sheave or other element, may be manipulated to move the cleaning element and thus serve the 60 double purpose of a controller for causing the valve to open and of an actuator for the cleaning element.

While we have illustrated and described with 65 particularity only a single preferred form of our invention, we do not desire to be limited to the exact structural details thus illustrated and described; but intend to cover all forms and arrangements which come within the definitions of the 70 invention constituting the appended claims.

We claim:

1. The combination with a movable soot cleaning element, of a valve to admit cleaning fluid thereto, a two-position controller to cause said valve to close when the controller is in one of its

positions and to open when the controller is in the second position, an actuator for said cleaning element to give it a predetermined movement, means including a catch associated with said actuator to move said controller into its said second position before the cleaning element has made more than a slight movement, and means actuated by said cleaning element to trip the catch and cause the shifting of the controller into the first of its said positions. 10

2. The combination with a movable soot cleaning element, of a valve to admit cleaning fluid thereto, a two-position controller to cause said valve to close when the controller is in one of its positions and to open when the valve is in the second position, said controller being movable automatically into the first of its said positions, an actuator for giving to the cleaning element a predetermined movement, means associated with the actuator to move said controller into its second position before the cleaning element has made more than a slight movement, a catch device to lock the controller in said second position and means controlled by the cleaning element to trip the catch and unlock the controller when the cleaning element has completed said predetermined movement. 20

3. The combination with a movable soot cleaning element, of a main pressure-responsive valve to admit cleaning fluid thereto, a two position 30 pilot valve to control the operation of the main valve movable automatically into one of its positions, an actuator for moving said cleaning element, means associated with said actuator to move the pilot valve into the second of its positions when the cleaning element is set in motion, 35 a catch device to lock the pilot valve in said second position and means controlled by the cleaning element thereafter to trip the catch and unlock the pilot valve after the cleaning element 40 has completed a predetermined movement.

4. The combination with a movable soot cleaning element, of a normally closed valve to admit cleaning fluid thereto, means to move said cleaning element step by step through a predetermined 45 series of steps, an actuator for said means, and means controlled by said actuator to cause said valve to open at the beginning of the first step in the movement of said cleaning element and controlled by said element to cause the valve to 50 close again when said element has completed said series of steps.

5. In a soot cleaning apparatus, a hollow head, a tubular cleaning element connected to the head, a valve controlling admission of cleaning fluid from the head to the cleaning element, a cylinder opening out of the head, a piston in the cylinder connected to the valve and exposed on one side to the pressure within the head, a spring acting on the piston in the direction to close the valve, and there being ports leading into the cylinder to admit fluid thereto and permit it to be exhausted therefrom, said ports being distributed lengthwise of the cylinder in such positions and of such a size that as the piston moves back to open the valve a large exhaust-port area is provided until the valve is fully open and then such area is greatly restricted to slow down the movement of the piston. 60

6. The combination with a movable soot cleaning element, of a valve for admitting cleaning fluid thereto, a valve controller, an actuator for said controller, means including a rotary driving member to move said cleaning element, an ec- 70

centric on said rotary member in position to engage and move said actuator, a catch for locking said controller and controlling means for said catch associated with the cleaning element.

5 7. In a soot cleaning apparatus, a hollow head, a tubular cleaning element connected to the head, a valve controlling admission of cleaning fluid from the head to the cleaning element, a cylinder opening out of the head, a piston in the cylinder connected to the valve and exposed on one side to the pressure within the head, a spring acting on the piston in the direction to close the valve, and there being ports leading into the cylinder to admit fluid thereto 10 and permit it to be exhausted therefrom, said ports being distributed lengthwise of the cylinder in such positions that as the piston moves back to open the valve a large exhaust-port area is provided until the valve is fully open and then such area is restricted to slow down the 15 movement of the piston.

20 8. The combination with a movable soot cleaning element, of a valve for admitting cleaning

fluid thereto, a valve controller, an actuator for said controller, means including a rotary driving member to move said cleaning element, an eccentric on said driving member in position to engage said actuator, a catch for holding said actuator in the position into which it is moved by the eccentric, a catch tripping device, and a part movable with said cleaning element adapted to engage with said catch tripping device.

9. The combination with a movable soot cleaning element, of a valve for admitting cleaning fluid thereto, mechanism for moving said cleaning element step by step, a driving member for said mechanism, a controller for said valve, means including a part on said driving member to operate said controller and lock it during a movement of the driving member of lesser extent than that required to cause the cleaning element to move through one step, and means movable with said cleaning element to unlock the controller of the cleaning element.
